CLAIM

The ornamental design for a combined automotive convertible roof, tonneau cover and rear compartment lid, as shown and described.

DESCRIPTION

The sole FIGURE is a perspective view of a combined automotive convertible roof, tonneau cover and rear compartment lid, showing the new design; the opposite view of the combined automotive convertible roof, tonneau cover and rear compartment lid is a symmetrically mirrored image of the FIGURE shown. The surfaces or portions of the article not shown in the drawings or described in the specification form no part of the claimed design; the broken line and fragmented line illustration of a portion of an automotive vehicle and parts thereof is for illustrative purposes only and forms no part of the claimed design.
